TIME DELAY SWITCHING DEVICE
Arthur George Wright, 7585 Raleigh St.,
Westminster, Colo. 80030
Filed Apr. 18, 1966, Ser. No. 543,249
24 Claims. (Cl. 200—61.04)

This application is a continuation-in-part application of my patent application Ser. No. 344,949, now abandoned, filed in the U.S. Patent Office on Feb. 14, 1964.

This invention relates to a switching device for use in electrical circuits, more particularly, it relates to a time controlled safety switching device which serves as a circuit component in the circuit it controls.

Prior art time controlled switching devices are ordinarily enclosed in a capsule having a switch gap and in operation a time controlled connector element for the points of the switch gap is released to connect the points of the switch gap after a pre-determined time. In these devices conducting lines from each branch of an outside circuit are connected to the points of the switch gap so that the connector element is the only element enclosed in the capsule which becomes a part of the outside circuit. In other words, the capsule itself does not serve as a link in the circuit when the circuit is closed so that the current does not pass through the capsule from end to end.

There are a large number of applications wherein it is desirable to use the capsule itself as a link in the circuit so that the use of circuit separate from the capsule is avoided. For example, in the use of explosives in oil wells wherein a time actuated bridge wire detonates the explosive it is desirable to use a conducting cable in a detonating circuit to lower the explosive to the point of use. It is advantageous to have a switching device incorporated in the cable which becomes a link in the circuit when the switch is closed. This arrangement eliminates the use of extraneous circuits, outside wires and other circuit components.

Accordingly, it is an object of this invention to provide a time controlled switching device which can be used in any type electrical circuit.

It is another object of this invention to provide an encapsulated switching device in which the capsule serves as a link in the circuit so that the circuit passes entirely through the capsule when it is closed.

It is another object of this invention to provide a switching device which can be incorporated as a link in a circuit including a conducting cable used for supporting objects.

It is another object of this invention to provide a switching device having a safety feature insuring that a circuit will be closed for a period of short duration only before it is reopened.

It is another object of this invention to provide a time controlled switching device in which the time period can be accurately and reliably controlled.

It is another object of this invention to provide a time controlled safety switching device which is adapted for use in a large number of applications and has a minimum of operating parts.

The above and other objects are accomplished by an encapsulated switching device comprising an insulating housing closed at both ends with conducting caps, each cap being electrically connected to terminals inside the

2

capsule, the terminal being spring biased toward their contact position and held in normally open position by a timing element so that upon elapse of a predetermined time the terminals are brought into contact. For providing a safety feature one of the terminals carries an insulating sleeve distal to its point of electrical contact with the other terminal so that after an instantaneous electrical contact of the terminals upon actuation of the timing means further relative movement between them is provided by the biasing means to cause breaking of the circuit by means of the insulating sleeve. In the preferred modification one of the terminals is in the form of a conducting plunger carrying an insulating sleeve distal to its contact point with the other terminal and the other terminal is in the form of a switch gap carried by a piston biased in the direction of the plunger and held in biased position by the timing means so that upon actuation of the timing means relative movement of the terminals causes the plunger to instantaneously contact the points of the switch gap followed by movement of the points in the direction of the plunger to contact the insulating sleeve to break the circuit. It is an important feature of the invention that the terminals are in electrical connection with the caps so that the device itself forms a link in the circuit when the switch is closed, and the current travels through the device from end to end.

The invention will now be explained with reference to the drawing wherein

FIG. 1 is a horizontal cross-sectional view of the switching device of the invention with the switch in open position and showing the closed position of the plunger in dotted lines;

FIG. 2 is a view similar to that of FIG. 1 showing the switch in the safe position, and

FIG. 3 is a vertical cross-sectional view taken on the line 3—3 of FIG. 1 looking in the direction of the arrows.

In the figures like parts are identified by like numerals with primes ('). In the description which follows only one of like members will be referred to and the numbers with primes ('') will not be mentioned.

The elements of the switching device are enclosed in a housing 10 of insulating non-conducting material, such as, polyethylene, Teflon or other type plastic. The material of the housing should be inert to ordinary solvents at least as it may come in contact with a wide variety of solvents. Steps 12 and seating surface 14 are formed at the end of the housing by machining or molding techniques. A connector sleeve 16 of conducting material, preferably metal, is press fitted over seating surface 14. The connecting sleeve 16 may be fitted over seating surface 14 by various means but it should be seated so that a fluid-type seal is effected between it and the seating surface. The connector sleeve 16 is provided with external threads 18.

As used in this specification and in the claims, the term "conducting material" includes metals, alloys, metal impregnated plastic, etc.

The housing 10 is closed at either end by a cap 20 having internal threads 22 mating with external threads 18 of the connector sleeve 16. The cap 20 is of conducting material as it is in the circuit path of current which travels through the switching device. An O ring 24 of elastic material, such as rubber, is seated between cap 20 and the end of connector element 16. The pur-

pose of this O ring is to insure that the interior of the housing is fluid tight.

A boss or plunger seat 26 is formed on the interior surface of cap 20 and supports plunger 28 which may be made integrally with the boss 26. The boss and plunger are of conducting material as they are components of an electrical circuit. The plunger 28 is bullet-shaped at its upper end 29 and is constructed to come to a point at the end as shown. A hollow insulating sleeve 30 is carried by the plunger. The insulating sleeve 30 may be made of suitable non-conducting material, such as various type plastics. It plays an important role in the safety feature of the invention and serves as a circuit breaker to break the current path through the switching device.

A movable electrode piston 32 is included in the housing beyond the plunger 28. The piston in the modification shown is of metal or other conductor as it serves as an element of an electrical circuit. The piston 32 is constructed with a hollow interior in which is seated an insulating liner 35 constructed with a cone-shaped inner chamber with the hollow pointed end designed to seat the end 29 of plunger 28. The end of piston 32 adjacent the plunger 29 is flared and a seat 36 is constructed in the flared portion to receive a pellet or time tablet 37. The pellet 37 serves as a timer to permit actuation of the switch mechanism to the closed and safety position. It is of soluble non-conducting material. It must be of non-conducting material because it holds the switch in open position. It must be soluble in a wide range of solutions or solvents which may be placed in the housing for dissolving or disintegrating it.

The pellet may be constructed of a wide range of materials and is not restricted to any particular material. A pellet constructed of aspirin, for example, would be suitable when used in connection with a solvent like water. The time period for actuation of the switch is governed by the material, density and solubility of the pellet and the solvent in conjunction with which it is used. There are other factors which vary the time period for actuation of the switch, such as, the concentration of the solvent, the size of the pellet, etc., but these are all within the skill of the art. A pellet-solvent combination which has been found to be effective is a product sold on the market as "Dow Resin PS-3," a polystyrene resin made by the Dow Chemical Company of Midland, Michigan, and a solution of methylene chloride. Various solvents which may be used with a suitable pellet material are aliphatic naphthas, aromatic solvents, ketones, ethers, acetates, alcohols, glycols, glycol ethers, amines, chlorinated solvents, water, and others. Examples of the wide variety of materials which may be used for the material of the pellet with suitable solvents are waxes, epoxy resins, polystyrene resins, silicone resins, phenolic and phenol-formaldehyde resins, glycerin-esterified resins, chlorinated rubber, vinyl resins, and others. The invention broadly includes the use of a pellet of solid material and a solvent in which it dissolves or disintegrates. It is not restricted to any particular pellet material or solvent as, obviously, any pellet material and a solvent in which it dissolves or disintegrates is a suitable combination. Gases and other means may be used for disintegrating the pellet. It is only necessary that the solution or disintegration of the pellet be controllable.

A spring seat 38 is machined in the outer surface of piston 32 on either side and a spring 39 of conducting material is mounted therein by means of screw 40 inserted in the wall of piston 32. Conducting contact point 41 is attached to the inner side of spring 39 and extends through the walls of piston 32 and sleeve 35. A switch gap is formed between the ends of contact points 41 and 41'. The spring must be of conducting material as it is in a current path to the switch and is an element of a circuit. Horizontal channels 42 are machined in the outer surface of piston 32 and circumferentially spaced around the piston. Longitudinally spaced ducts or bores 43 connect

these channels with the interior of the piston. A boss 46 made integral with piston 32 is provided on the end of the piston distal to the plunger 28. The boss 46 is constructed with an inner channel 48 and an outer circumferential seating groove 50. A spring 52 is seated between the boss 46 and the boss 26' of cap 20' by means of a groove 50. The spring must be of conducting material as it serves as an element of a circuit for the passage of current through the switch.

Referring to FIG. 1, the assembly of the device is as follows: The cap 20' is inserted over the end of the housing by means of connector element 16' with O ring 24' in place. With the device held in upright position, with cap 21' serving as the bottom of the capsule, solution is poured into the capsule to fill it about two-thirds full. The piston 32 with spring 52 having one end seated in groove 50 is then inserted into the capsule and the other end of the spring seated on boss 26'. Before the insertion of the piston 32 into the capsule, the pellet 37 is seated in the seat 36. Cap 20 is now brought into position for attachment to connector 16. The end 29 of plunger 28 is inserted in the end of hole 56 in the pellet 37 and the assembly of piston 32 and spring 52 compressed in the direction of cap 21 until threads 18 of connector 16 mate with threads 22 of cap 20 and the cap 20 is then screwed into final position.

Referring again to FIG. 1 for a description of the completed assembly, it will be seen that piston 32 is biased in the direction of plunger 28 and is held in biased position by the contact of pellet 37 with the end 29 of plunger 28. With the switch assembly in this position it will be seen that a continuous circuit path is provided from cap 20' through spring 52, piston 32, flat springs 39-39' to points 41-41'. It will also be seen that a continuous circuit path is provided from cap 20 to the end 29 of the contact area of plunger 28.

The operation of the device is as follows: The capsule is inverted to bring the solution in contact with the pellet 37. When the pellet 37 is dissolved or sufficiently disintegrated to no longer withstand the biasing force of spring 52, piston 32 will move in the direction of plunger 28 so that the conducting end 29 of plunger 28 will contact the points 41-41' and complete a continuous circuit through the switching device from cap 20' to cap 20. The conducting elements of the circuit are cap 20', biasing spring 52, piston 32, flat springs 39-39', points 41-41', plunger 28 and the cap 20 and they form a continuous circuit path or conducting path. At this point of travel of piston 32 current will flow through the switching device with the device being a link in the circuit or current path. As the contact points 41-41' are resiliently mounted by means of springs 39-39', the piston will continue to travel under the biasing force of spring 52 in the direction of plunger 28 until the contact points have passed beyond the conducting area 29 of plunger 28 and come to rest on insulating member 30, the continuous circuit being broken as soon as the contact points 41-41' come in contact on either side with insulating sleeve 30. It will be noted that the contact points 41-41' now rest on the insulating sleeve 30 and the end 29 of plunger 28 is seated in the pointed area of insulating liner 35. The device is now ready for disassembly and recharging for re-use and can be used over and over. It will be noted that the switching device sequentially changes from a safe condition as shown in FIG. 1 to a condition in which the circuit is closed as shown in dotted lines to a final safety position as shown in FIG. 2. The time in which the circuit remains closed will, of course, depend upon the strength of spring 52 and the consequent rate of travel of the piston as well as the size of the relative contact areas 29 of plunger 28 and contact points 41-41'.

The switching device can be enclosed in a power-pac device with the conducting end caps 20-20' in conducting relationship with components of a circuit and the power-pac inserted 75 in a conducting cable to be used for lifting, lowering ex-

plosives into a hole, etc. Thus assembled, the switching device serves as a timing switch for a circuit and becomes a link in the circuit when the circuit is closed. It should be mentioned that the materials of the timing pellet 37 and the solution for it are so selected that no galvanic action is produced during the action of the solution on the pellet or by the reaction products formed. The solution is, of course, in contact with the exposed surface of the pellet 37 and comes in contact with the interior surface of the pellet 37 by traveling through channels 42 and bores 43 into the interior of the liner 35.

Various alternative equivalent structures and features to those disclosed will be apparent to those skilled in the art. For example, the points 41-41' and plunger 28 can be biased for relative movement toward each other by other arrangements, such as, the piston being fixed and the plunger being spring-biased toward it with the spring positioned between the end of the plunger and cap 20, or springs can be used between both the plunger and the piston and the respective adjacent end caps. Furthermore, as the points 41-41' constitute one electrical terminal contact within the housing and the connecting area 29 of the plunger 28 constitutes another electrical terminal contact, the two terminals which are brought in contact to complete the circuit through the device can take various forms and are not limited to a switch gap and a plunger. For example, the piston can be replaced by another plunger hinged at its base to pass over contact area 29 of plunger 28 and travel on down to contact insulating sleeve 30. While the timing means for controlling the actuation of the switch to the closed position is disclosed as a pellet which dissolves or disintegrates in the solution, other timing means, such as, electrical timing means can be used. The use of the pellet and a solution in which it dissolves is exemplary of the preferred timing means.

The switching device of the invention can be used without utilizing the safety feature. For example, the time pellet 37 may be made of conducting material, such as, metalized plastic, and the device used to break a circuit after a predetermined time. The safety feature is most commonly used in conjunction with the use of explosives. With a conducting pellet being used, the circuit would be closed with the elements of the device in the position shown in FIG. 1. After the conducting pellet has dissolved or disintegrated, the circuit will be broken and the piston will move relative to the plunger to place the contact points 41-41' in contact with insulating sleeve 30 wherein the device will be in the position shown in FIG. 2.

While the combination of a solid pellet 37 and a solution for dissolving it has been disclosed as a timing means, the pellet can obviously be dissolved or disintegrated by other means, such as, gases, pressure, etc. The important thing is that there be no galvanic action created by the pellet and the solvent or the reaction products thereof, and the disintegration or solution of the pellet be controllable. As used herein the term "soluble" includes the property of the material to dissolve or disintegrate in gaseous and other mediums as well as liquids and the term "solvent" includes gaseous and other mediums as well as liquids.

The switching device disclosed herein can be used in any circuit; however, it finds special application in bridge plugs, packers, selective timers, electromagnetic fishing tools, retrieval apparatus, oil well equipment involving explosives, remote control switches, etc.

It is seen from the above description that a simple switching device having a minimum of operating parts has been provided which can be used in any type electrical circuit. The device has the advantage that the timing period can be reproducibly altered and controlled by varying the material of the time pellet and the solution and the characteristics of these two elements. It can also be varied by adjusting the strength of the spring 52 and by other means which will be obvious to those skilled in the art. The device provides a safety device insuring 75

that if a bridge wire in a circuit for detonating an explosive does not function during the closed period of the circuit, the circuit condition will be altered to safe so that the equipment can be removed, and the bridge wire replaced, or other corrective action taken. The chief advantage of the device over the prior art is that when it is in the closed circuit condition it becomes a link in the circuit with the conductive elements of the device forming a current path through the device, thus eliminating the use of external circuits and parts.

It will be understood that other modifications than those disclosed are possible without departing from the spirit of the invention or the scope of the claims.

I claim:

1. A switching device comprising, in combination: a housing of insulating material; an electrically conducting closure means at both ends of said housing; a first electrical terminal contact means in said housing connected to one of said closure means in electrically conducting relationship; a second electrical terminal contact means in said housing attached to said other closure means in electrically conducting relationship and adapted to contact said first electrical terminal contact means in electrically conducting relationship; a timing element of soluble material holding said terminal contact means out of contact for a predetermined time; a solvent for said soluble element in said housing; whereby upon elapse of said predetermined time said terminal contact means come in contact and a continuous conducting path is established between said conducting closure means at both ends of said housing.

2. The switching device of claim 1 in which at least one of said terminal contact means is biased to move in the direction of the other terminal contact means.

3. A switching device comprising, in combination: a housing of insulating material; an electrically conducting closure means at both ends of said housing; a first electrical terminal contact means in said housing connected to one of said closure means in electrically conducting relationship and including a switch gap with terminal points; a second electrical terminal contact means in said housing attached to said other closure means in electrically conducting relationship and adapted to contact and connect said terminal points of said switch gap in electrical conducting relationship; means for breaking electrically conducting contact between said electrical terminal contact means after they are in contact; and means for forcing said electrical terminal contact means sequentially in and out of electrically conducting contact with each other; and timing means holding said terminal contact means out of contact with each other for a pre-determined time whereby upon elapse of said pre-determined time said terminal contact means come in contact and a continuous conducting path is established between said conducting closure means at both ends of said housing.

4. A switching device comprising, in combination: a housing of insulating material; an electrically conducting closure means at both ends of said housing; a first electrical terminal contact means in said housing connected to one of said closure means in electrically conducting relationship; a second electrical terminal contact means in said housing attached to said other closure means in electrically conducting relationship and adapted to contact said first electrical terminal contact means in electrically conducting relationship; timing means holding said terminal contact means out of contact for a pre-determined time; whereby upon elapse of said pre-determined time said terminal contact means come in contact and a continuous conducting path is established between said conducting closure means at both ends of said housing; means for breaking electrically conducting contact between said electrical terminal contact means after they are in contact, and means for forcing said electrical terminal contact means sequentially in and out of electrically conducting contact with each other.

5. The switching device of claim 4 in which said timing means is an element of soluble material.
6. A switching device comprising, in combination: a housing of insulating material; an electrically conducting closure means at both ends of said housing; a first electrical terminal contact means in said housing connected to one of said closure means in electrically conducting relationship and including a switch gap with terminal points; a second electrical terminal contact means in said housing attached to said other closure means in electrically conducting relationship and including a conducting plunger having a conducting contact area adapted to contact and connect the contact points of said switch gap and having an insulating area distal to said contact area positioned to be sequentially contacted by said contact points following their contact with said conducting contact area; at least one of said electrical terminal contact means being biased to move in the direction of the other terminal contact means; said electrical terminal contact means constructed to be held apart for a predetermined time by timing means and to move in contact with each other after elapse of said predetermined time.
7. The switching device of claim 6 including timing means holding said terminal contact means out of contact for a predetermined time.
8. A switching device comprising, in combination: a housing of insulating material; an electrically conducting closure means at both ends of said housing; a hollow piston in said housing carrying a first electrical terminal contact means including a switch gap having at least two terminal points extending into the hollow of said piston and being connected to one of said closure means in electrically conducting relationship; a second electrical terminal contact means in said housing attached to said other closure means in electrically conducting relationship and adapted to contact said first electrical terminal contact means in electrically conducting relationship; an electrically conducting biasing spring between the end of said piston distal to the other of said terminal contact means and one of said closure means; timing means holding said terminal contact means out of contact for a predetermined time; whereby upon elapse of said predetermined time said terminal contact means come in contact and a continuous conducting path is established between said conducting closure means at both ends of said housing.
9. The switching device of claim 8 in which said timing means is an element of soluble material.
10. A switching device comprising, in combination: a housing of insulating material; an electrically conducting closure means at both ends of said housing; a piston carrying a first electrical terminal contact means in said housing connected to one of said closure means in electrically conducting relationship; a second electrical terminal contact means in said housing attached to said other closure means in electrically conducting relationship and adapted to contact said first electrical terminal contact means in electrically conducting relationship; a biasing means between the end of said piston distal to the other of said terminal contact means and one of said closure means; timing means holding said terminal contact means out of contact for a predetermined time; whereby upon elapse of said predetermined time said terminal contact means come in contact and a continuous conducting path is established between said conducting closure means at both ends of said housing; and means associated with one of said terminal contact means for breaking electrically conducting contact between said electrical terminal contact means after they are in contact, said biasing means being operative to force said electrical terminal contact means sequentially into electrical contact with each other and into position in which said breaking means is effective to break said electrically conducting contact.
11. The switching device of claim 10 in which said timing means is an element of soluble material.
12. The switching device of claim 6 in which said insulating area is comprised of a sleeve of insulating material.
13. The switching device of claim 6 including a piston carrying one of said terminal contact means and a biasing means between the end of said piston distal to the other of said terminal contact means and one of said closure means.
14. The switching device of claim 8 in which said terminal points are resiliently mounted.
15. The switching device of claim 10 in which said breaking means is an insulating sleeve.
16. A switching device comprising: a housing of insulating material closed at both ends with caps of electrically conducting material; a plunger of electrically conducting material mounted internally of said housing in electrically conducting relationship with one of said caps and provided with an insulating sleeve distal to its free end; an electrode piston in said housing in electrically conducting relationship with the other of said caps and having an internal chamber; a pair of opposed spring biased conducting elements supported by said piston in electrically conducting relationship therewith extending through the wall of said piston into said chamber and forming a switch gap for an electrical circuit; biasing means between the end of said piston distal to said plunger and said other of said caps biasing the piston in the direction of said plunger; and a pellet of soluble material supported at the other end of said piston in contact with the free end of said plunger and holding said piston in biased position.
17. The switching device of claim 16 including an insulating sleeve in said chamber.
18. The switching device of claim 17 in which said piston and said biasing means are of electrically conducting material.
19. The switching device of claim 16 in which said soluble element is of non-conducting material.
20. The switching device of claim 16 in which said soluble element is of a conducting material.
21. The switching device of claim 1 in which said element is made of polystyrene and said solution is methylene chloride.
22. A switching device comprising, in combination: a housing of insulating material; an electrically conducting closure means at both ends of said housing; a first electrical terminal contact means in said housing connected to one of said closure means in electrically conducting relationship; a second electrical terminal contact means in said housing attached to said other closure means in electrically conducting relationship and adapted to contact said first electrical terminal contact means in electrically conducting relationship, at least one of said terminal contact means being biased to move in the direction of the other contact terminal means; a timing element of soluble material located between said terminal contact means and holding said terminal contact means out of contact for a predetermined time; whereby upon elapse of said predetermined time said terminal contact means come in contact and a continuous conducting path is established between said conducting closure means at both ends of said housing.
23. A switching device comprising, in combination: a housing of insulating material; an electrically conducting closure means at both ends of said housing; a first electrical terminal contact means in said housing connected to one of said closure means in electrically conducting relationship; a second electrical terminal contact means in said housing attached to said other closure means in electrically conducting relationship and adapted to contact said first electrical terminal contact means in electrically conducting relationship, at least one of said terminal contact means being biased to move in the direction of the other contact terminal means; said electrical terminal contact means constructed to be held apart for a predetermined time by timing means and to move in

contact with each other after elapse of said predetermined time; means for breaking electrically conducting contact between said electrical terminal contact means after they are in contact; and means for forcing said electrical terminal contact means sequentially in and out of electrically conducting contact with each other.

24. The switching device of claim 23 including timing means holding said terminal contact means out of contact for a predetermined time.
